HAND BAG

Application filed June 22, 1928. Serial No. 287,425.

This invention relates to hand bags, and more particularly to hand bags such as carried by ladies for containing a purse, trinkets and so forth.

5 The objects of the invention are to provide an improved bag which may be utilized as an under-arm bag or as a bag to be carried by its handle; to give the bag the appearance of not having a handle when used as an under-arm bag; to provide a handle which will space the gripping portion of the handle away from the body of the bag when the handle is used; to provide a handle which will be slidably secured to the bag; to protect 10 the bag against being opened by sneak thieves while being carried; to secure simplicity of construction and operation; and to obtain other advantages and results as may be brought out in the following description.

15 Referring to the accompanying drawing in which like numerals of reference indicate similar parts throughout the several views;

20 Figure 1 is an elevation of a bag embodying my invention showing the same as it appears when used as an under-arm bag;

Figure 2 is a sectional view on line 2—2 of Fig. 1;

25 Figure 3 is a view similar to Fig. 1 showing bag with handle in position for use; and

30 Figure 4 is a sectional view on line 4—4 of Fig. 3.

In the specific embodiment of the invention illustrated in said drawing, the reference numeral 1 indicates the body portion of the bag which provides a hinged frame 2 as usual, adapted to be closed together and secured by a snap lock 3 thereby providing a closed pouch for containing a purse 4 and providing ample space therein for other contents. Said body portion 1 provides an outer casing 5 and an inner wall 6 on each side of the bag thereby providing a slip pocket 7 between the said outer casing and inner wall. The outer casing and inner wall are stitched 45 together at their ends, as at 8, the outer cas-

ing preferably extending as one piece of material from the upper edge of the bag downwardly under the bag and up to the opposite upper edge of the bag so as to give a very neat and pleasing appearance and eliminate unnecessary crevices and stitching. For purposes of properly finishing the bag I preferably line the inner wall on both sides and provide an inner lining to the outer casing. These linings may also be continuous from the upper edge of the bag around under the bottom of the bag to the upper edge of the opposite side if so desired.

50 Within the slip pocket 6, I position my improved handle 9 which preferably comprises a piece of material of the same character as comprises the outer casing of the bag, this handle being slidable into and out of said slip pocket. The upper part of this handle is shown as recessed at 10 for insertion of the user's hand in grasping the handle. Across the top of said handle I have shown a bar 11 or other gripping means which preferably is of a construction to give the appearance of being the upper frame of the bag at such time 55 as the handle is slid down into the pocket, as shown in Figure 1. In such position of the handle, the bag is very attractive and usable as an under-arm bag with no outward appearance of having a handle at all, and the handle 60 is obviously slid into the bag out of the way so the bag may be used very conveniently and satisfactorily. At the lower end of the handle I preferably utilize a very flexible material, such as silk 12, which is stitched near 65 the bottom of the bag to the inner lining. The portion of the handle which is exposed is preferably of a less flexible character thus enabling the handle to be pushed into the slip pocket without any difficulty or any 70 crumpling of the normally exposed part. Consequently the lower portion of the handle which is of a more flexible material will be 75 the part that crumbles and thus the bag is 75 kept in presentable shape at all times with 80 85 90 95

no exposed wrinkled parts and no disfiguring bulges from crumpled material since the silk used on the lower end of the handle is sufficiently thin to crumble without taking any material space.

5 It will be observed that as I prefer to construct the bag, the handle is made of several parts permanently secured together, namely the upper bar of celluloid or other suitable material secured across the upper edge of 10 upper handle portion which is all moderately stiff material, such as leather, and the third part of the handle comprises the very flexible lower portion which is never exposed and which is preferably of silk. It is to be understood, however, that I do not limit myself to 15 constructing the handle of these specific parts nor do I restrict myself to building the handle from several separate pieces, as obviously it may be constructed otherwise. It is also to 20 be noted that I preferably provide a handle in each of the slip pockets, that is, a handle at both sides of the bag. Consequently when the handles are withdrawn for carrying the bag thereby, it will be observed that said 25 handles are on opposite sides of the pouch frame and consequently will prevent a sneak thief from gaining access to the pouch by opening the frame. Furthermore, the 30 handles will pull out of the slip pockets a sufficient distance so that the user's hand may enter through the cut-out portion of the handles and readily and securely grasp the same when the bag is to be carried in that 35 manner.

Obviously detail changes and modifications may be made in the construction and use of my improved hand bag, and I do not wish to be understood as limiting myself to the exact 40 construction shown or described except as set forth in the following claims when construed in the light of the prior art.

Having thus described my invention, I claim:

45 1. A hand bag comprising a body portion having a slip pocket, a handle secured at its lower end in said pocket, the upper portion of said handle being slidable at its upper portion into and out of said slip pocket.

50 2. A hand bag having slip pockets on opposite sides thereof, handles at opposite sides of the bag having their lower ends secured in said slip pockets, the upper portions of said handles being slidable into said slip pockets.

55 3. A hand bag providing a slip pocket, a handle having a lower flexible portion secured entirely within said slip pocket, said handle having a less flexible upper portion permanently secured to said flexible lower 60 portion and slidable into and out of said slip pocket by virtue of the flexibility of the lower portion.

4. A hand bag providing a slip pocket, a handle having a lower flexible portion secured entirely within said slip pocket, said

handle having a less flexible upper portion permanently secured to said flexible lower portion and slidable into and out of said slip pocket by virtue of the flexibility of the lower portion, said handle having a bar along the upper edge of said less flexible portion, said bar providing a hand hold when the handle is slid out of the pocket and said bar extending along the upper edge of the bag in exposed position when the handle is slid into said pocket.
